MICROTOME

David Danon, 16 Henkin St., Rehovoth, Israel
Filed June 29, 1962, Ser. No. 206,305
Claims priority, application Great Britain, July 3, 1961,
24,009/61
8 Claims. (Cl. 83—267)

It is an object of the present invention to provide an improved microtome. It is a further object of the present invention to provide an improved microtome by means of which it is possible to effect any predetermined unit of advance of the specimen, within predetermined limits. It is still a further object of the present invention to provide a novel microtome with which any unit of advance between 0 to about 3000 A. is possible, wherein the specimen cutting operation is not effected during the advance of the specimen and which is entirely mechanical in its operation. Other and further objects of the present invention will become apparent hereinafter.

The invention consists in a microtome comprising a system of two levers, one of which is adapted to be raised in units of 1 micron by means of a gear system including a micrometric screw, the second lever being adapted to be raised by first lever through the intermediary of a pin arranged at a distance from its fulcrum, the second lever carrying a rotatable drum near said fulcrum, on which drum the specimen is mounted, the rotation of the drum being adapted to move the specimen past a cutting knife and to actuate the system for raising said first lever.

The invention is illustrated, by way of example only, in the accompanying drawings, in which:

FIG. 1 is a side elevation, partly in section of the microtome according to the invention;

FIG. 2 is a plan view thereof;

FIG. 3 is a front elevation partly in section thereof;

FIG. 4 is a partial section taken on line IV—IV of FIG. 2;

FIG. 5 is a section taken on line V—V of FIG. 4. A base 1 supported at three points, i.e., two integral legs 2 at its front and one similar leg 2 at the median line near the back is provided with integral left and right side walls 3, 4, respectively and back wall 5. A shaft 6 extends between walls 3, 4 near their bottom and is journaled in bearings mounted therein. To the shaft 6 is fixed a ratchet wheel 9 which is turned by a detent 10 in a manner to be hereinafter described. To the center of shaft 6 a worm 11 is keyed which is in mesh with a worm wheel 12 mounted on a vertically extending shaft 13 turnably supported on its bottom end on a steel ball 14 lodged in a suitable depression of base 1. The shaft 13 is threaded with a micrometric screw thread whose pitch is equal to 1 millimeter and which is turnably held in a nut 15 having a similar internal thread, the nut being housed for vertical but non-turnable movement between two upright guides 16 integral with and projecting from the side wall 3. For every rotary advance of one tooth of ratchet wheel 9 worm 11 and worm wheel 12 cause shaft 13 to make such a turn that nut 15 is raised by micron. An upwardly extending angle bracket 17 is integral with nut 15 and supports with its horizontal upper leg a ball 18 on which rests the truncated apex of a lever 19 made of glass or of metal covered with glass, having the shape of a substantially isosceles triangle, the other two corners being supported on balls 20, 21 lodged on the top of the rear wall 5 in a manner to be described hereinafter, the balls constituting the fulcrum of the lever. The distance between ball 18 and the line joining balls 20, 21 has a predetermined integral dimension. A second lever 22 constituted by a substantially rectangular plate

2

has a cut-out 23 at its front end, the two sides 24 bordering said cut-out being supported on the tops of the front end of walls 3, 4 by means of balls 25, 26, respectively, in a manner to be hereinafter described, the balls 25, 26 constituting the fulcrum of lever 22. The other support for lever 22 comprises a pin 27 slidable in an elongated slot 28 in the median line of lever 22 and having an enlarged pointed bottom end 29 which rests on lever 19, the top end of pin 27 being threaded for engagement with a nut 30 by which pin 27 can be fixed in any position along the slot 28 and thus along the distance between the ball 18 and balls 20, 21.

In the top faces of sides 24, substantially V-shaped depressions 31 are provided in which the shaft 32 carrying a drum 33 keyed to the shaft is journaled, the depressions constituting the bearings for the shaft 32. The drum 33 is constituted by a solid body whose center portion is cylindrical, the sides 33' being truncated cones whose ends contact the side walls 24. The center portion of the drum carries a known specimen holder 34 which is fixed in position by a set screw 35. To the ends of the shaft flywheels 36 are keyed, one of the flywheels having a handle 37 fixed to it. One side 33' of the drum (i.e., the left one as seen in FIG. 3) has an eccentric undercut on which sits the annular upper end 10' of detent 10 being held on the undercut by an eccentric retaining member 38 fixed to the drum. The bottom part of the detent 10 is bifurcated into a shorter and a longer prong 10a and 10b, respectively, the longer prong 10a being adapted to engage the ratchet wheel 9. The movement of the detent 10 is governed by a lever 39 fixed with one end to the side wall 3 and having a lug 39' projecting from its other end and extending into the slot between the prongs 10a and 10b. It can be seen with the position of lever 39 as shown in FIG. 1, that with each revolution of the shaft 32 the detent moves ratchet 9 counterclockwise by one tooth, which causes, as has been described hereinbefore, nut 15 and thus bracket 17 and ball 18 to be raised in units of 1 micron, whereby the proximal point of lever 19 is similarly raised. The position of lever 39 may be changed, e.g., so that lug 39' lies against the outside of prong 10a, to cause prong 10a to move ratchet 9 by two teeth for each revolution of shaft 32, i.e., to cause lever 19 to be raised in units of 2 microns.

The knife 40 is mounted on a tool post 41 which is mounted for both longitudinal and transverse adjustment on base 1, the arrangement being similar to the tool post of a lathe. This arrangement is known with microtomes and does not form part of the invention.

The support of lever 22 on balls 25, 26, and that of lever 19 on balls 20, 21 is effected in a manner so as to allow their exact disposition even with a slight intolerance in the measurements of the support points of the levers. This construction is shown in FIG. 4 with respect to supports 25, 26, but the same construction applies to supports 20, 21. The ball 25 is lodged between two registering conical bores 42 in side 24 and side wall 3, respectively, while the ball 26 is lodged between a conical bore in the other side 24 and a transverse groove of triangular cross-section in the side wall 4.

The position of the specimen holder 34 and that of the detent 10 on the drum is fixed in such a manner that only after the specimen holder 34 upon the rotation of the drum has passed the knife 40 to effect a cut of the specimen mounted on the holder, will the detent 10 effect the rotation of the ratchet 9 to raise lever 19 around its fulcrum 20, 21 to position the axis of shaft 32 for the following cut. Depending on the position of pin 27 between points 18 and 20, 21, and of the distance of the pin from supports 25, 26 the rais-

ing of the lever 19 by 1 micron is reduced accordingly, whereby the axis of drum 33 around this fulcrum is angularly displaced correspondingly.

I claim:

1. A microtome comprising a first and second lever; a gear system including a ratchet wheel, a micrometric screw threaded shaft operatively driven by the ratchet wheel, and a nut on said threaded shaft held against rotation on said micrometric screw, said nut having an extension engaging said first lever for raising said lever as said nut moves up said rotating screw, a pin operated by said first lever and engaging said second lever to raise said second lever, a rotatable drum carried by said second lever, a specimen carried by said rotating drum, a cutting knife, rotation of said drum moving said specimen past said cutting knife, an eccentric member having a detent mounted on said drum to engage and operate said ratchet wheel once for each revolution of said drum, the relative position of said specimen and said detent on said drum being such that upon rotation of said drum, the specimen moves past the cutting knife before the gear system is actuated by the detent for the next cutting operation.

2. A microtome comprising a first and second lever, means for moving said first lever through micron units of distance; the second of said levers being adjustable and in operative relation with said first lever and movable thereby at a distance from the fulcrum of said second lever for effecting a distance movement reduction, a rotatable drum advanced by said second lever adjacent said fulcrum and a stationary cutting knife, said drum carrying a specimen past said cutting knife, said drum advancing said specimen on each rotation toward said knife under control of said second lever, said means for moving said first lever being controlled by said drum for operating said first lever following cutting of said specimen by said knife.

3. A microtome comprising a first and second lever, means for moving said first lever through micron units of distance; the second lever being in operative relation with said first lever and movable thereby at a distance from the fulcrum of said second lever for effecting a distance movement reduction, a rotatable drum advanced by said second lever adjacent said fulcrum and a stationary cutting knife, said drum carrying a specimen past said cutting knife, said drum advancing said specimen on each rotation toward said knife under control of said second lever, said moving means being controlled by said drum for operating said first lever following cutting of said specimen by said knife.

4. A microtome comprising a first and a second lever, means for moving said first lever through micron units; said second lever in operative relation with said first lever and movable thereby at a distance from the fulcrum of said second lever for effecting a distance reduction, a rotatable drum journaled on V-bearings operated by said second lever adjacent said fulcrum and a stationary cutting knife, said drum carrying a specimen past said cutting knife, said drum advancing said specimen on each rotation toward said knife under control of said second lever, said moving means being controlled by said drum for operating said first lever following cutting of said specimen by said knife.

5. A microtome comprising a first and a second lever, means for moving said first lever through micron units

of distance; said second lever having a glass surface in operative relation with said second lever and movable thereby at a distance from the fulcrum of said second lever for effecting a distance reduction, a rotatable drum operated by said second lever adjacent said fulcrum and a stationary cutting knife, said drum carrying a specimen past said cutting knife, said drum advancing said specimen on each rotation toward said knife under control of said second lever, said moving means being controlled by said drum for operating said first lever following cutting of said specimen by said knife.

6. A microtome comprising a first lever, means for moving said first lever through micron units of distance; a second lever in operative relation with said first lever and movable thereby at a distance from the fulcrum of said second lever for effecting a distance reduction, means for adjusting one of said levers, a rotatable drum operated by said second lever adjacent said fulcrum and a stationary cutting knife, said drum carrying a specimen past said cutting knife, said drum advancing said specimen on each rotation toward said knife under control of said second lever, said moving means being controlled by said drum for operating said first lever following cutting of said specimen by said knife.

7. A microtome comprising a first and second lever, means for moving the first lever through micron units of distance; the second lever being in operative relation with said first lever and movable thereby at a distance from the fulcrum of said second lever for effecting a distance reduction, means for adjusting one of said levers, a rotatable drum operated by said second lever adjacent said fulcrum, the shaft of said drum being journaled in V-shaped depressions, the drum having oblique side walls contacting said depressions, and a stationary cutting knife, said drum carrying a specimen past said cutting knife, said drum advancing said specimen on each rotation toward said knife under control of said second lever, said moving means being controlled by said drum for operating said first lever following cutting of said specimen by said knife.

8. A microtome comprising a first and second lever, means for moving the first lever through micron units of distance; the second lever being in operative relation with said first lever and movable thereby at a distance from the fulcrum of said second lever for effecting a distance reduction, means for adjusting one of said levers, a rotatable drum operated by said second lever adjacent said fulcrum and a stationary cutting knife, said drum carrying a specimen past said cutting knife, said drum advancing said specimen on each rotation toward said knife under control of said second lever, said moving means being controlled by said drum for operating said first lever following cutting of said specimen by said knife.
